CLAIM

The ornamental design for an automobile rearview mirror, as shown and described.

DESCRIPTION

FIG. 1 is a front perspective view of an automobile rearview mirror showing my new design as a flat mirror with a gradually curved left end thereof;

FIG. 2 is a front perspective view of an automobile rearview mirror showing a second embodiment of my new design;

FIG. 3 is a front elevational view of both FIGS. 1 and 2;

FIG. 4 is a rear elevational view of both FIGS. 1 and 2;

FIG. 5 is a top plan view of FIG. 1;

FIG. 6 is a bottom plan view of FIG. 1;

FIG. 7 is a top plan view of FIG. 2;

FIG. 8 is a bottom plan view of FIG. 2;

FIG. 9 is a left side elevational view of FIG. 1;

FIG. 10 is a right side elevational view of FIG. 1;

FIG. 11 is a left side elevational view of FIG. 2; and,

FIG. 12 is a right side elevational view of FIG. 2.
